UNITED STATES PATENT OFFICE.

LAWRENCE P. CRECELIUS, OF CLEVELAND, OHIO, ASSIGNOR TO THE ELECTRIC RAILWAY IMPROVEMENT COMPANY, OF CLEVELAND, OHIO, A CORPORATION OF OHIO.

APPARATUS FOR UNITING METAL BODIES.

1,294,409.

Specification of Letters Patent.

Patented Feb. 18, 1919.

Application filed April 30, 1915. Serial No. 24,931.

To all whom it may concern:

Be it known that I, LAWRENCE P. CRECELIUS, a citizen of the United States, residing at Cleveland, in the county of Cuyahoga and State of Ohio, have invented a certain new and useful Improvement in Apparatus for Unitting Metal Bodies, of which the following is a full, clear, and exact description.

This invention relates to apparatus for uniting metal bodies adapted particularly for rail bonding purposes, and is an improvement over the rail bonding apparatus constituting the subject matter of the application of Paul H. Eberlein and myself, Serial No. 759,074, filed April 5th, 1913, (patented Oct. 9, 1917, and numbered 1,242,524).

Apparatus for uniting metal bodies by means of either one or two heating electrodes which are pressed against one or both the bodies to be united are well known in the art and have been employed for brazing copper bonds to steel rails. In one well known construction the operating parts of the apparatus are carried by a car which runs on the rails of the track to be bonded. These operating parts include a single heating electrode which is adapted to be pressed against the bond, and suitable electrical apparatus consisting of a rotary converter and transformer, one of the terminals of which is connected to the electrode and the other being grounded so that the current will pass from one terminal of the transformer through the electrode, bond and rail to the other terminal of the transformer.

In the Crecelius and Eberlein application above referred to, there is disclosed a rail bonding apparatus which is small and compact and is designed to be clamped to the rail in such a way that it does not obstruct the track being bonded. Additionally, this apparatus includes two heating electrodes mounted on a carrier in such a way that both may be pressed with variable pressures against the terminal of the bond, these electrodes being connected to the terminals of the current source in such a way that the current passes through the electrodes and bond in series. With this apparatus, and especially because of the use of the two series connected electrodes the current required for bonding is reduced to such an extent that small leads may be employed and

the apparatus may, therefore, be carried by hand from point to point along the track.

The main object of the present invention is to provide an apparatus which has all the advantages of the Crecelius and Eberlein apparatus above briefly described, but which reduces still further the current required for brazing or otherwise uniting two metal bodies, and also reduces the time required for the uniting operation.

This is accomplished by mechanism having a high resistance heating electrode which is designed to be pressed against one of the bodies to be united so as to heat the same by conduction, and means for creating an arc in the electric circuit at the electrode so that the heating effect of the current passing through the electrode will be intensified by the arc. In the specific embodiment of my invention here shown, two electrodes are utilized, although two are not essential, and the arcing is created between the electrodes and the part which they are adapted to engage and heat, by vibrating the electrodes.

The invention may be further briefly summarized as consisting in certain novel combinations and arrangements of parts which will be described in the specification and set forth in the appended claims.

In the accompanying sheet of drawings wherein I have shown two forms of my invention, Figure 1 is a side elevation of my improved rail bonding apparatus applied to the rail, the apparatus here shown having a mechanical electrode vibrator; Fig. 2 is a section substantially along the line 2—2 of Fig. 1; Fig. 3 is a top plan view of the same; Fig. 4 is a sectional view substantially along the line 4—4 of Fig. 1; Fig. 5 is a top plan view showing a modification which is provided with an electrically-operated electrode vibrator; and Fig. 6 is a side view of the same.

Referring now to the drawings, and first to Figs. 1 to 4, 10 represents a rail which may be regarded as a rail of the track to be bonded. The apparatus embodying my invention is attached to the rail and is supported at one side of the same so that the gage line is clear and unobstructed, this apparatus including a rail clamp composed of two parts 11 and 12, which are adapted to grip opposite sides of the rail flange, as shown particularly in Fig. 1, and the parts

being adapted to be clamped to or unclamped from the rail by a suitable adjusting screw 13. The part 11 of the clamp plate has secured to it a plate 14 whose front 5 edge is undercut, as shown, and is parallel to the rail when the clamp is in position. Mounted on this plate is an electrode carrier in the form of a base 15 provided on its lower side with a projected flange 15^a, which 10 is adapted to engage the front edge of the plate 14. This construction permits the carrier 15 and all parts supported thereby to be easily and quickly removed from the clamp, or to be placed in position and properly supported and to be adjusted lengthwise of the rail to properly position the electrodes with reference to the bond terminal or with reference to the point to which the terminal is to be attached. In this particular 15 instance the carrier 15 supports two electrodes, this carrier being provided with a pair of undercut slots or guideways which receive a pair of slides 16 to which are secured by screws 17 a pair of box like electrode holders 18 insulated from each other and from the slides and carrying high resistance heating electrodes 19 preferably composed of carbon. These holders 18 are provided with quick detachable coupling 20 members 20 to which are adapted to be connected complementary coupling members 21 attached to transformer leads 22, one of which is shown in Fig. 3.

With this construction, when both the 25 heating electrodes 19 are pressed against the terminal of the bond which is designated 23, the current will pass from one electrode into the terminal of the bond and from the bond into the other electrode. In other words, 30 current passes through the two electrodes and bond with the three parts in series relationship. This feature or use of the two series electrodes is embodied in the apparatus disclosed in the Crecelius and Eberlein 35 application previously referred to. As disclosed in said prior application, the bond is heated by conduction from the two electrodes, by the heat generated at the points of contact between the electrodes and the bond, and by the current itself passing 40 through the bond from one electrode to the other. The pressures of the electrodes on the bond terminal and the heating effects can be adjusted by adjusting screws connect- 45 ed to the slides, so that the portions of the terminal opposite both electrodes will be uniformly heated.

In accordance with the present invention, the bond is heated by the high resistance 50 electrodes by conduction and also by the passage of current through the bond and by the heat generated at the points of contact between the electrodes and bond, as in the prior construction, and in this case it is heated 55 additionally by rapidly moving the elec-

trodes away from and toward or against the terminal so as to create a rapid arcing, which brings the terminal of the bond and the adjacent portion of the rail to brazing temperature much more quickly or with less 70 current than with the prior construction. This part of the apparatus will now be described.

It will be observed that each of the slides has connected to it an adjusting screw 25, 75 which has a threaded connection with the slide and passes loosely through the outer end 15^a of the carrier 15. The electrodes are pressed against the terminal of the bond and the adjusting screws are normally held 80 in a certain definite position with collars 26 bearing against the outer face of the end 15^a of the carrier by coil springs 27, which surround the adjusting screws, and are arranged between the end 15^a of the carrier 85 and collars or abutments 28 fixed to the adjusting screws. By adjusting the screws 25, the electrode holders may be moved toward or from the terminal of the bond, so as to adjust the pressures of the electrodes against 90 the bond.

To produce the vibrating or arcing effect previously referred to, the adjusting screws are rapidly and alternatively pulled outwardly, and then released so that the springs 95 may restore the screws and electrodes to normal position with the electrodes bearing against the bond terminal. In the construction shown in Figs. 1 to 4, this is done mechanically by mechanism including a short 100 shaft 30 rotatably supported by a bracket 31 secured by screws 32 to the end 15^a of the carrier 15, and by a plate 31 supported on the adjusting screws 25. This shaft is provided with a disk 33 having a series of camming lugs or ribs 34, which as the disk is rotated are adapted to engage the beveled faces or disks or other suitable abutments 35 secured to the adjusting screws 25 a short 105 distance in front of the collars 26, and force 110 the members 35 outwardly. When the shaft 30 is turned by hand, the ridges of the disk 33 engaged the two beveled members 35 alternately, alternately retracting the adjusting screws 25 and the electrodes 19. As soon 115 as one of the ribs rides off of the member 35, the spring 27 restores the adjusting screw 25 and electrode to normal position with the end of the electrode bearing against the bond terminal. In consequence, the electrodes are alternately withdrawn from the bond terminal, and then quickly restored 120 against the same, producing the arcing which heats both the electrodes and the bond terminal very quickly with less current than 125 would be required if the two electrodes were permitted to bear continuously against the bond terminal, as in the Crecelius and Eberlein application before referred to. Consequently, I am enabled by the improvement 130

just described to reduce the size of the rotary converter and transformer and to reduce the size of the leads connecting the electrodes to the transformer, and this gives the apparatus still greater flexibility in use.

In the construction shown in Figs. 5 and 6, the electrodes are vibrated electrically by means of a magnet, which is mounted on the end of the carrier 15. This magnet includes a core 36 which is preferably formed of laminated material and is supported from the carrier 15 by bracket arms 36^a. This core is surrounded by a coil 37, one terminal of which is connected by a connector 38, to one of the electrode holders here designated 39; these holders supporting electrodes 19 similar in all respects to those first described. The other terminal of the magnet coil 37 is adapted to be connected by a connector or coupler composed of two parts 40 and 41 to one transformer terminal 42, the other transformer terminal 43 being adapted to be connected to the other electrode holder, as in the construction first described. This magnet also includes an armature or so-called keeper 44, which is preferably composed of laminated material, this armature being mounted between the end of the carrier 15 and the magnet core 36, and having openings through which the adjusting screws 25 pass, these adjusting screws 25 being connected to the slides to which the electrode holders are secured, as previously described. Each of the adjusting screws 25 is provided with a collar or shoulder 45 shown by dotted lines in Fig. 5, which shoulder is fitted in a recess on the rear face of the armature, as shown.

It will be observed from the construction described, that when the circuit is completed through the electrodes and bond terminal, the magnet is energized because the coil 37 is in series in the circuit. Upon the energization of the magnet, the armature is attracted toward the magnet core and pulls both adjusting screws outwardly, withdrawing the electrodes 19 from the terminal of the bond. As soon as they are withdrawn from the bond the circuit is broken, the magnet is deenergized, and the springs 27 immediately restore the electrodes against the bond terminal, causing the circuit to be again completed, and the magnet to be energized. With this construction, therefore, the electrodes are rapidly vibrated to and from the bond terminal, causing the arcing the same as with the mechanical vibrator shown in Figs. 1 to 4. There is this difference, however, in the action of two vibrators, that with the first described construction the electrodes are alternately withdrawn from the bond terminal, one electrode being in engagement, while the other is out of engagement with the terminal, whereas with the electric vibrator, both electrodes are with-

drawn from and restored to the bond terminal simultaneously. With the mechanical vibrator which withdraws the two electrodes alternately from the bond terminal, the terminal will be held in place against the rail by the electrodes themselves whereas with the electric vibrator, some other means should be provided to hold the bond in place when both electrodes are withdrawn therefrom. Any suitable means may be provided for this purpose, but in the drawings I have shown a simple device consisting of a clamp composed of an arm or bracket 46, which is secured to the carrier 15, and a spring-pressed finger or clip 47, the arm and finger being shaped to constitute jaws which grip the bond near the terminal thereof and hold the same in position independently of the action of the electrodes.

The construction of the apparatus shown in Figs. 5 and 6 is otherwise the same as that shown in Figs. 1 to 4, and the description given in connection with the first construction will suffice for the corresponding parts of the second construction, corresponding or similar parts bearing the same reference characters.

It will be observed that in neither construction does the vibrator affect or interfere with the manual adjusting of the pressures of the two electrodes against the bond terminal, but in the event one electrode heats the bond terminal more rapidly than the other, by means of the adjusting screws 25, the relative pressures of the electrodes on the terminal can be adjusted or varied to bring about equal or predetermined heating effects opposite both electrodes. In fact, if desired, one of the electrodes can be moved inwardly against the bond terminal with such pressure that it will not be vibrated or moved away from the terminal by the vibrator, and this can be done without affecting the action of the vibrator on the other electrode.

While I have shown my invention applied to rail bonding apparatus, I wish it to be understood that my invention may be utilized under other conditions or for other purposes than that of bonding rails. Furthermore, while I have shown the invention applied to apparatus having two electrodes, it will be obvious that it can be used equally well with a single electrode, in which event the circuit will be from one terminal of the transformer or other source of current through the electrode and through the bond terminal and then either from the bond or from the rail back to the other terminal of the transformer or source of current. It will be understood also that if a single vibrating electrode is employed, it will be desirable to support the bond terminal or other member to be united to the rail or second metal member, by a clamp or other

suitable holding device, and this will be true whether the electrode is vibrated mechanically or electrically.

Additionally, it will be understood that 5 the form of the apparatus including the manner of mounting or supporting the electrode or electrodes, as the case may be, and also the means for vibrating the electrode or electrodes may be varied considerably 10 from the constructions shown. Especially is this true of the vibrators, which can be constructed and operated in many specifically different ways.

In the foregoing description I have referred 15 to the fact that with this apparatus the bonds are brazed to the rail, and it will be understood that in practice suitable brazing material will be placed between the bond and the rail. When the apparatus is used 20 for uniting copper bonds to steel rails, and when the heating electrodes are applied to the bonds, as in this case, the bonding can be done only by brazing or soldering, but the apparatus may under certain conditions 25 be used for welding together two metal members, especially if the electrode or electrodes are pressed against the member having the higher fusion or melting temperature.

30 I, therefore, do not desire to be confined to the exact details shown, but aim in my claims to cover all modifications, constructions and applications of the invention which do not involve a departure from the 35 spirit and scope of my invention herein described.

Having described my invention, I claim:

1. In an apparatus for uniting metal bodies, a support, a high resistance heating 40 electrode carried by the support and adapted to be pressed against one of the bodies to be united so as to heat said body by conduction, and means for causing a relative movement between said body and the 45 electrode whereby one of said parts is moved into and out of engagement with the other so as to cause an arcing between said parts at the point where the electrode heats said body by conduction.

50 2. In an apparatus for uniting metal bodies, a support, an electrode carried by the support and adapted to be pressed against one of the bodies to be united, yieldable means for pressing the electrode 55 against said body, means for alternately withdrawing the electrode from said body and then releasing the same, and means for adjusting the pressure of the electrode against the body when the electrode is in contact with the said body.

55 3. In a rail bonding apparatus, a clamp adapted to support an electrode at the side of the rail, a heating electrode carried by said support and adapted to press a bond terminal against the rail, and means for vi-

brating said electrode to cause the same to alternately move away from and then into contact with the bond terminal.

4. In a rail bonding apparatus, an electrode support, one or more high resistance 70 heating electrodes mounted on said support at the side of the rail, means for pressing the electrode or electrodes against a terminal of the bond engaging the rail, and means acting in opposition to said means for repeatedly or periodically moving the electrodes away from the bond. 75

5. In a rail bonding apparatus, an electrode support, one or more electrodes mounted on said support at the side of the rail, 80 means for pressing the electrode or electrodes against a terminal of the bond engaging the rail, means acting in opposition to said means for repeatedly or periodically moving the electrode or electrodes away 85 from the bond, and means for adjusting the pressure of the electrode or electrodes against the bond when the former are in engagement therewith.

6. In an apparatus for uniting metal 90 bodies, a support, a pair of electrodes carried by said support and arranged side by side and adapted to be pressed against one of the bodies to be united while said body is in engagement with the second body, and 95 means for vibrating both electrodes so as to cause them to alternately move away from and then move in contact with the body which they are adapted to engage.

7. In an apparatus for uniting metal 100 bodies, an electrode support, a pair of electrodes carried thereby and arranged side by side so as to bear against one of the bodies to be united while the latter is engaging the second body, means for adjusting the pressures of said electrodes against the body which they engage, and means for vibrating the electrodes to cause them to alternately move away from and into contact with the body which they are adapted to engage. 105 110

8. In an apparatus for uniting metal bodies, an electrode support, one or more high resistance heating electrodes carried by the support and adapted to bear against one of said bodies so that the latter will be 115 heated by conduction, means for pressing the electrode or electrodes against said body with predetermined pressure, and means for causing said electrode or electrodes to be vibrated relative to the body opposite the 120 point or points where the electrode or electrodes heat said body by conduction.

9. In an apparatus for uniting metal bodies, an electrode support, a pair of electrodes mounted side by side on said support 125 and adapted to bear against one of the bodies to be united to a second body, means comprising yieldable springs for pressing the electrodes against said body with predetermined pressures, and means for alter- 130

nately moving electrodes away from said body and then releasing the same whereby the electrodes are vibrated relative to the body.

- 5 10. In an apparatus for uniting metal bodies, an electrode support, a pair of electrodes mounted on said support side by side and adapted to bear against one of the bodies to be united to a second body, means comprising yieldable springs for pressing the electrodes against said body with predetermined pressures, means for alternately moving the electrodes away from said body and then releasing the same, whereby the electrodes are vibrated relative to the body, and means for varying or adjusting the pressures with which the electrodes bear against said body while in engagement therewith.
- 10 15. In a rail bonding apparatus, a clamp adapted to engage a rail, an electrode support carried by said clamp and located at the side of the rail when the clamp is secured to the rail, one or more electrodes carried by said support and adapted to bear against the bond terminal, and means for vibrating the electrode or electrodes against the bond terminal.
- 15 20. 11. In a rail bonding apparatus, a clamp adapted to engage a rail, an electrode support carried by said clamp and located at the side of the rail when the clamp is secured to the rail, one or more electrodes carried by said support and adapted to bear against the bond terminal, and means for vibrating the electrode or electrodes against the bond terminal.
- 20 25. 12. In an apparatus for uniting metal bodies an electrode support, a high resistance heating electrode carried thereby and adapted to engage one of said bodies and thereby heat the same by conduction, and electrically operated means for vibrating the electrode opposite the point or area where it engages and heats the body by conduction.
- 25 30. 13. In an apparatus for uniting metal bodies, an electrode support, a pair of electrodes arranged side by side, means whereby
- 30 35. 14. In a rail bonding apparatus, an electrode support, an electrode carried by said support and adapted to press the bond against the rail, means for vibrating the electrode, and means for supporting said bond in position against the rail independently of the electrode.
- 35 40. 15. In an apparatus for uniting metal bodies, a support, a high resistance heating electrode carried thereby and adapted to be pressed against one of the bodies to heat the same by conduction, means for supplying an electric current to the electrode to heat the same, and means for moving one of the elements of the electric circuit so as to produce an arc at the electrode whereby the latter is brought to a high temperature.
- 40 45. 16. In an apparatus for uniting metal bodies, means for applying heat externally to one of the bodies, comprising a heating electrode adapted to be pressed against one of the bodies to heat the same by conduction, means for passing a heating current through the electrode and means for moving one element of the electric circuit so as to produce an arc which intensifies the heat imparted to the electrode and to the body adjacent thereto.

In testimony whereof, I hereunto affix my signature in the presence of two witnesses.

LAWRENCE P. CRECELIUS.
